BIRGER JOHNSEN, OF LONG BEACH, CALIFORNIA, ASSIGNOR OF ONE-HALF TO FRED-
ERICK L. HANCOCK, OF LONG BEACH, CALIFORNIA.

CARBONATING AND DISPENSING APPARATUS.

Application filed December 30, 1924. Serial No. 758,956.

This invention relates to apparatus for carbonating water and has for an object to provide a multiple draft-arm, master control valve system.

5 An object is to provide for the positive prevention of any back flow of gas into the main water supply line, such as occurs past the usual check valve when this, for any reason does not close tightly. An object is 10 to provide a precooling of the water before carbonization so that its saturation coefficient is made much greater. An object is to provide for service of ice water at will from the pre-cooler and yet check any back 15 gas pressure into the pre-cooler. An object is to introduce fresh water into the top of a mixing chamber and to take carbonated water from the bottom to insure a thorough mixing of gas and water before the water 20 can pass from the chamber. In this connection an object is to provide for the whirling of the gas bubbles into large pockets rather than a direct confined narrow channel line of flow.

25 An object is to provide a system including a plurality of draft arms, a simple, master valve train for fresh water, gas and snift control, and a suitably operated master valve control; the draft arms being independently operative, but under control of the master valve for service of carbonated water.

An object is to provide a service counting system.

30 An important object is to provide for the automatic expulsion of freed air from the carbonator by a snifting means, and to provide a cut-off means to prevent water from flowing after the snifted air.

35 An object is to provide displaceable means for creating additional liquid space in the chamber so as to provide capacity for entrance of gas in the event water should completely fill the chamber and so tend to bar entrance of the gas into the chamber.

40 Other objects and advantages will be made manifest in the following specification of an embodiment of apparatus of the invention; it being understood that other modifications, 45 variations and adaptations may be resorted to within the spirit of the invention and the scope thereof as here claimed.

The invention consists of structure and method whereby the objects are accom-

plished, and one structure is illustrated in 55 the accompanying drawings, wherein:

Fig. 1 is a diagram of a service counter with which the invention is combined.

Fig. 2 is a vertical cross-section of the top 60 of the carbonating apparatus.

Fig. 3 is a longitudinal section of a part of a syrup manifold.

Fig. 4 is a plan of a baffle.

Fig. 5 is a vertical section of a draft arm 65 structure.

Fig. 6 is a face view of the draft arm port head.

Fig. 7 is a diagram of the draft arm lever index segment.

Fig. 8 shows a carbonated water measuring 70 means.

Fig. 9 is a detail of valve operating cam means.

The present system or apparatus includes 75 a shell 2 forming a carbonating chamber adapted to be disposed in any suitable or standard ice box or cooler, as C in the counter A shown.

In the chamber 2 is series of upwardly convergent hoods 3 with flanges 4 spaced 80 around the rims of saucers 5 just under the hoods. Each saucer forms a large water pocket below its upper hood. Spacers 6 support the baffle forming hoods and a saucer 85 in a column extending up from the bottom 8 of the shell, to the top of which is connected a cold water pipe 9 leading from a master valve to be referred to later.

Around the shell is a cooler tank from 90 which pipe 9 leads at the bottom. Fresh water comes in by a pipe 7.

The upper part of shell 2 has a cap 11 closing the chamber. In this cap is a valve rest 12 having open ports 13 leading to a valve space 14 in which a valve 15 is 95 disposed with a stem 16 playing in the rest 12. Above the valve is a seat 17 having collar 18 attached to the cap 11. From the seat 17 extends a snift tube 19.

A small bleed port 20 provides for equalization of pressure between the snift line and the valve space.

Displaceable means are provided to press the valve 15 to its seat 17 after collected air has escaped. Such means also has the function of deformation under pressure to provide for admission of carbonic gas through a bottom inlet 22 of chamber 2. If the

- chamber 2 is full of water gas cannot enter. Therefore, I provide a deformable means, as a rubber ball 21, below the cap 11 to provide gas space. As carbonated water is drawn from the outlet 23 in the bottom of chamber 2 the buoyant ball 21 descends and the snift valve 15 drops from its seat 17, allowing accumulated air to snift away. While the gas valve is open there is 120 pounds pressure in the carbonating chamber and as the dispenser is opened the water level falls under this pressure until water pressure in pipe 9 overcomes pressure in the carbonator chamber. Then the fresh water rises and closes valve 15 by ball 21. Fresh water enters from the pipe 7 while carbonated water is flowing out and when the ball 21 is lifted it presses the snift valve 15 to its seat 17 and snift is cut off.
- 20 When the chamber is again full of water the ball closes the port 17^a to prevent water from getting to the snift line 19. Gas pressure equalization is established through the bleed port 20.
- 25 The present system provides a master valve device normally opening the gas line 22 and normally closing the snift line 19 and the fresh water pipe 9.
- 30 The master device has a water valve W, a gas valve G, and a snift cock S. The pipe 9 connects to the outlet from the valve W whose supply side is attached by pipe 9^a to pre-cooling tank 10 which has a branch 9^c for ice water to draft arms D.
- 35 It is very desirable to provide a positive safety against any back flow from the carbonator to the water tank pipe 9^a, which is connected to tank 10, and so avoid expensive loss of gas by leakage past the usual check valve V. The water valve W is provided to assure no leak past the check to the tank 10.
- 40 The snift tube 19 leads to cock S, and from this to a receiver R. The gas pipe 22 leads to gas cock G having a supply line 26.
- 45 The cock G is automatically opened and valves W and S are automatically closed preferably by a master device as a spring thrust rod P.
- 50 A feature of the invention is provision of multiple draft-arms D at the counter or at suitable locations adapted to receive carbonated water from the single carbonator chamber 2, under control of the master water valve W. Means are provided for operating the master valve device (W-S-G) from the location, or station, of any of the draft arms D.
- 55 From the outlet 23, in the bottom of the chamber 2, extends a carbonated water conduit 24, having branches 25 to the draft arms D, and having a valve 27 suitably connected to a manually operated mechanism, including rod P linked to the valve 27.
- 60 At each station is a counting instrument

D to register each opening of the station draft arm valve by the attendant. The register may be connected to any operating station part effecting the valve 27. This valve must be opened before any liquid will flow from the opened draft-arm.

Normally the gas is passing to the chamber 2 through the open gas valve G and the water is saturated by the gas which, being of higher pressure than that in the water line 9, tends to flow past check valve V and cause a constant loss as well as to allow the water in the carbonator to flatten. But in my present apparatus this loss is prevented by the main valve W, which is a tight and positive cut off when closed. So, also, the gas cannot leak back to the pre-cooler 10 or pass to the ice-water pipe 9^c.

The operation is as follows:

The attendant at any station, desiring to dispense carbonated water from the near draft-arm, depresses his station arm 28 and this acts to open the carbonated water valve 27. As the arm is operated it pushes a bar 30 and this causes a lever 31 to pull up the rod P which throws gas valve G to close and cut off gas flow, and will positively open the valves W-S to supply pre-cooled water to the chamber through the stand pipe 9, and at the same moment open the snift line 19 to let out air and open carbonated water valve 27.

The water supply pipes are all large enough to supply plenty of fresh water in event several of the draft-arms should be open at the same time. After accumulated air is forced out and the chamber begins to fill with fresh water the ball (or equivalent means) rises and closes the snift valve 15 against seat 17. Any number of the levers 31 can be actuated after master valve device, as rod P has been shifted by another, and the action of each arm will be counted or registered by its register I. The rod will be effective until the last lever (in use) is released, and then is restored by its spring 32 and the valve device W-S-G set normal.

When the rod P is restored, the gas is turned on by cock G. It flows to the chamber 2 and exerts a compression on the water which compresses the deformable (compressible) device 21 which therefore provides additional space allowing entrance of the gas at the bottom of the chamber.

The entering gas whirls from saucer to saucer and hood to hood in the chamber and thus has ample time, and large area of contact, for absorption by the water. When the gas pressure is fully established in the chamber it works past the ball 21 and bleeds through the port 20. This equalizes pressure in the snift line to valve S and allows the valve 15 to settle when the ball again falls away.

In Figs. 6 and 7 is shown a draft-arm

providing for selection of any of a variety of syrups from jars J, and for a combination of syrups or of a syrup and water. The structure includes a manifold M to which is connected a series of tubes 41 from the jars J to a draft arm. A head block 42 has ports 43 from the tube ends to its bottom face 44 against which bears a valve disc 45 having a single port 46 registering with a port 47 in a block 48. This block supports disc 45 and has a king-pin 49 with a ball-bearing race 50 in the head block. The ports 43 terminate in a circular row in the face 44 so that when the valve block is swung around the port 46 may register with any port 43.

Arm 28 is pivoted in a bracket (not shown) on block 48 and has a lug 28^a to engage the near end of the bar 30 which is thrust forward by its spring 51 in the block. Under the block is a measuring cup 52 having a guide 53 for a valve stem 54 on whose upper part is a valve disc 55 thrust against the bottom of block 48 by a spring 56 so as to normally close duct 47 leading from port 46 in the disc 45.

The cross-bar 30, in the block 48, has a cam 30^a engaging the top end of stem 54 and has a notch 30^b back of the cam. If the cross-bar 30 is apposed to the heel of the lever 31 then when the arm 28 is pressed down the bar not only acts on lever 31 to pull up the master valve rod P but also pushes down the valve 55 and opens duct 47 allowing flow to the cup 52. When this is full a signal discharge flows through a small passageway 58 leading from the upper end of stem 54 out at its bottom. This will provide for "fizzing" carbonated water while a bottom valve 59 on the stem 54 closes the outlet from the cup. To give full stream discharge the cam-bar 30 is pushed over until the stem 54 slips up into the notch 30^b; valve 59 lifting from the outlet seat 60. To select a service tube port 43, the arm is thrown laterally and this swings the valve port 46 to the desired port, or to a position to register with two of the ports when a "mix" is desired.

After register is obtained as shown by an index segment 62 on the head, the arm is then depressed one step and liquid flows to the cup while the valves 55-59 are depressed. When the cup is full this is indicated by flow from passageway 58. Then the arm is released, valve 55 moves up closing port 47, and the bar 30 is swung around to register with carbonated water valve lever 31. Handle 28 is then depressed two steps to bring bar notch 30^b over stem 54 and move valves 55-59 to neutral positions for free flowing of carbonated water from a tube 41 and through cup 52. The cam bar 30 is apposed to lever 31, at only two positions to serve carbonated water. The segment 62 has two index notches to permit such

registering position, and also has a deep notch for fresh water service.

Fresh water is discharged when the bar 30 engages a lever 65 having a heel disposed to be so engaged, attached to a water valve 66 Fig. 1. Suitable connections from each draft arm D, are made to actuate the master valve rod P. These may include rock shafts 67 with cams 67^a to engage a lift plate 68 attached to rod P, the rock shafts 75 being operated by the respective station draft arm rods P and levers 31.

A feature of this invention is to utilize gas or air pressure snifted off from the carbonator to force syrup from a jar J through its tube 41 to the head of any draft arm D. As shown, the snifted air is discharged into a receiver R from which it passes in pipes 69 to boxes or manifolds M into the bottom of which the jars screw. Over each jar is a valve device to close the manifold hole when the jar is removed. This device includes a springing diaphragm 70 having a central nipple 71 free around the tube 41 leading down into the jar and having a valve seat 72 for the end of the nipple when the jar is screwed out. An applied jar engages a ring 73 on, and forces back, the diaphragm so that air can pass into the jar and dispel liquid through its tube 41.

A suitable air pressure is automatically maintained on the receiver R by a control means of suitable type; here shown as including an upright tube 75 of U-form holding a heavy liquid, as mercury, proportioned to sustain, say five pounds, of air pressure. If the pressure goes up too high the mercury rises and spreads out in a pan 76 allowing the excess air and water coming over if any, to escape, whereupon the valve forming 105 mercury will immediately counterbalance again to hold the pressure desired.

Means may be introduced in the carbonated water pipe 24 to measure out given quantities of carbonated water at each service. Such means is shown in Fig. 8 as including a cylinder 80 having a back flow check valve 81 at its inlet end and at its opposite end having discharge connections 25^a for the different draft arms. In the cylinder is a piston 82 having a valve member 83 to close outlets 83^a to the discharges. From the piston extends a rod 84 forced outward by a spring 85 to close the outlets 83^a. In the piston is a by-pass valve 86 held to its seat 87 by a spring with a pressure greater than the frictional resistance of the piston and rod in or against their guides. The master rod P when, pulled up, connects, as by dog 88, with the rod 84 and shifts piston 80 a desired degree regulated by an adjustable screw stop 89, liquid moving past the valve 86 during the shift. When the dog is tripped, carbonated water and spring pressure returns the piston with a discharging 130

action, overcoming friction but not opening the by-pass valve 86. The pipe 25 is attached to the back of block 42 in the same manner as the tubes 41, which is clearly shown in Fig. 5.

My invention consists of the novel method and apparatus above described.

What is claimed is:

1. A carbonating apparatus having, in combination, a carbonating chamber, a plurality of draft-arms connected thereto, a control valve for each draft-arm to supply carbonated water, and a master fresh water valve connected to said chamber and combined with said control valves to operate with any one of said valves.
2. A carbonating apparatus having, in combination, a carbonating chamber, a draft-arm having conduit connection therewith, a manually operated service control valve for the draft-arm, a master water valve for supplying the chamber with fresh water, a snift valve, a gas supply valve and a liquid controlled snifting cut-off valve for the chamber and means operatively connecting the fresh water valve, the service control valve and the gas and snift valves.
3. A carbonator having, in combination, a carbonating chamber, a draft-arm having conduit connection therewith, a normally closed service control valve for the draft-arm, a normally closed valve for fresh water to the chamber, a normally closed snift control valve for the chamber, an automatic snift cut-off in the chamber, and a normally open gas valve for gas to the chamber and means operatively connecting the fresh water valve, the service control valve and the gas and snift valves.
4. A carbonator having, in combination, a carbonating chamber, a draft-arm having conduit connection therewith, a normally closed service control valve for the draft-arm, a normally closed valve for fresh water to the chamber, a normally closed snift control valve for the chamber, an automatic snift cut-off to close the snift outlet, a nor-

mally open gas valve for gas to the chamber, and manually operable means for concurrently closing the gas valve, and opening the water, snift and service control valves.

5. A carbonator having, in combination, a carbonating chamber, a plurality of draft-arms independent of each other, a normally closed service control valve for each draft-arm, a normally closed valve for fresh water to the chamber, a normally open valve for gas to the chamber, a normally closed, liquid operated air snifting means for the chamber, and means operative with any one of the service control valves for reversing the condition of the other valves.

6. A carbonating chamber having a displaceable means operative by admitted gas pressure to yield in the chamber and provide space for the entrance of gas, when the chamber is filled to capacity with water retarding entrance of the gas.

7. A carbonating chamber having a snifting outlet for air, liquid operated means for closing the outlet, and means for equalizing pressure around the closed outlet to release the closing means.

8. A carbonating chamber having at its top an outlet port to snift off air, a valve to cover the port and cut off snift of air, and a float operative on the valve to close it, and a by-pass around the port.

9. A carbonating apparatus having, in combination, a carbonating chamber, a service draft-arm, a conduit connecting the chamber and the draft arm, and means for measuring the carbonated water discharges and including a cylinder to which said conduit leads and then extends to the draft arm, a back flow check valve in the cylinder, a piston in the cylinder having a valve to cut off discharge from the cylinder, a by-pass in the piston, means to automatically shift the piston to effect a discharge from the cylinder, and a draft arm actuated means for setting the piston at measuring position.

BIRGER JOHNSEN.
